UNITED STATES PATENT OFFICE.

ROBERT T. MORRISON, JR., OF MEDINA, OHIO, ASSIGNOR OF ONE-HALF TO
GEORGE D. BILLINGS AND ABNER B. BISHOP, BOTH OF SAME PLACE.

CAR-COUPING.

SPECIFICATION forming part of Letters Patent No. 297,152, dated April 22, 1884.

Application filed February 11, 1884. (No model.)

To all whom it may concern:

Be it known that I, ROBERT T. MORRISON, Jr., of Medina, in the county of Medina and State of Ohio, have invented certain new and useful Improvements in Car-Couplers; and I do hereby declare the following to be a full, clear, and exact description of the invention, such as will enable others skilled in the art to which it pertains to make and use the same.

10 My invention relates to improvements in car-couplers, the object being to provide a coupling-pin pivoted to the draw-head in such a manner that it will automatically receive the link and couple the cars. A further object is to provide mechanism by means of which the coupling-pin may be raised and the cars uncoupled from either side or on top of the cars. A further object is to provide a weight pivoted to the draw-head that will hold 20 the link in position to engage other draw-heads in coupling cars. A further object is to provide a cup attached to the weight that will prevent snow, rain, and ice from entering the chambers of the draw-head. With these 25 objects in view my invention consists in certain features of construction and in combination of parts, hereinafter described, and pointed out in the claims.

In the accompanying drawings, Figure 1 is 30 a vertical section of the draw-head, coupling-pin, weight, and link in position, and arranged according to my invention. Fig. 2 is a view in perspective of the weight and coupling-pin. Fig. 3 is a view in perspective of 35 the mechanism for operating the coupling-pin from the side or top of the car.

A represents the draw-head, with a vertical chamber, A', extending through the draw-head from top to bottom, and opening into 40 the flaring chamber A'', that receives the link. The top and bottom walls, a and a', of the chamber A'' diverge to such an extent, as they extend toward the front end, that a link held by another draw-head that is considerably 45 higher or lower will be guided to its place to engage the coupling-pin.

B is the weight, chambered at B', so as to 50 embrace the coupling-pin C, so that both are pivoted on the pin D, extending through the draw-head. The weight B is provided with

the cover b, that covers the recess A', so as to exclude snow, rain, or ice from the chamber. An opening, b', extends from the top of the cap b through the weight to the chamber B', through which passes the link c, attached to 55 the coupling-pin C, and by means of which the said pin may be raised and the cars uncoupled. When the link E is thrust into the draw-head, it raises the pin C and the weight B. After it has sufficiently entered, the pin C drops 60 back in its place, securing the link, while the weight rests on the top of the link and holds it by means of the seat a' in about a horizontal position. As the weight is pivoted, as aforesaid, it will rise or fall to accommodate any 65 position that the link may assume, but without interfering with the coupling-pin or cramping the link. When the link is only engaged in the draw-head A, it will remain, as shown in Fig. 1, in a suitable position to 70 engage the draw-head of other cars as they approach for coupling. As aforesaid, by means of the link or rod e, the coupling-pin may be raised at any time and the cars uncoupled.

75 A rod, F, may be provided, that is secured by staples or other suitable means across the end of the car at a convenient distance above the draw-head. This rod at the center is provided with the horizontal arm F', that at 80 the end is attached by any suitable means—such, for instance, as a link or chain, G—to the link c. A similar attachment, g, leads to the top of the car. The rod F at both sides of the car is provided with the arms f. By 85 means of these attachments the coupling-pin may be raised from either side or from the top of the car, or from between the cars when necessary.

90 What I claim is—

1. The pivoted weight B, provided with the cover b, and the chamber B', adapted to receive the coupling-pin and the opening b', substantially as set forth.
2. The combination, with the draw-head, of 95 a coupling-pin pivoted at its upper end to the draw-head, a weight also pivoted to the draw-head and provided with a groove in which the coupling-pin rests, and a chain or other device attached to the free end of the coupling- 100

pin and passing upwardly through the weight, substantially as set forth.

3. The combination, with a draw-head, of the coupling-pin pivoted to the draw-head, 5 the weight B, pivoted to the draw-head and provided with a groove in which the coupling-pin rests, and with a seat, *a*, adapted to rest on the link and hold it in position to engage the coupling-pin of the approaching draw-
10 head, substantially as set forth.

4. The combination, with the coupling-pin

C, arranged as aforesaid, of the rod F, provided with the arms F' and *f* and the connections G and *g*, substantially as set forth.

In testimony whereof I sign this specification, in the presence of two witnesses, this 15 28th day of January, 1884.

ROBERT T. MORRISON, JR.
